GLASS FEEDER

Frank L. O. Wadsworth, Pittsburgh, Pa., assignor
to Ball Brothers Company, Muncie, Ind., a cor-
poration of Indiana

Application August 28, 1933, Serial No. 687,044

35 Claims. (Cl. 49—55)

My invention relates to an automatic glass feeder of the self-controlled-continuous-forced-flow type, which is broadly differentiated from the usual forms or species of flow feeding devices by its capacity to establish and maintain an uninterrupted flow of substantially greater volume than can be obtained either by the action of gravity alone—as in natural flow feeders—or by the combined action of gravity and of an intermittently applied and periodically reversed force—as in reciprocating plunger and pressure-vacuum air types of apparatus—and one of the principal objects of my improvements is to thus greatly augment the rate of delivery of the molten material, both by increasing the mean effective extrusion pressure thereon, and by also eliminating the loss of time (and the other difficulties) which is occasioned by the periodic stoppage and reversal of the expulsion movement thereof.

My improved type of feeder is further differentiated from those now in common use by its capacity to control its own action in such manner as to obtain a uniformity of operative performance, and secure a preadjusted or predetermined character of delivery, that is best adapted to produce a series of mold charges of the proper contour and weight for subsequent fabrication in the forming machine with which the feeder is to be used; and another important purpose of the present invention is to provide a method and a means of procedure whereby these results may be effectively attained under a wide variation in operative conditions.

Another object of my improvements is to provide means for periodically varying and controlling the extrusion pressure—and the resultant rate of discharge of the molten glass—for the purpose of "shaping" successive sections of the continuously flowing stream (without interrupting the continuity of flow), prior to its separation into mold charges; and thereby obtaining a uniform series of progressively formed "gobs" or masses of material that may be readily severed from the oncoming stream (preferably at points of reduced diameter) and delivered to the receiving apparatus in the best condition for the desired treatment therein.

A further purpose of these improvements is the provision of readily adjustable instrumentalities for manually regulating the relative variations in the rate of delivery of the continuously flowing material during different portions of each complete cycle of "gob" formation; and thus changing, when desired, the form or contour of successive stream sections, without altering the

mass or volume of the series of mold charges cut therefrom.

Still another object of this invention is the provision of a special form of delivery orifice ring, which is particularly adapted to cooperate with other features of my improved feeder construction in securing the results that are characteristic of the combination as a whole; or which may be used with advantage in conjunction with other analogous forms of apparatus.

Additional purposes and objects of the herein described improvements will become apparent, to those skilled in this art, from a consideration of the two exemplary embodiments thereof, which are illustrated in the accompanying drawings, and in which:

Figure I is a longitudinal vertical section through the center of one form of my improved feeder assembly;

Fig. II is a horizontal section (on a reduced scale), on the double plane II—II—II of Fig. I;

Fig. III is a partial vertical section, in the plane of Fig. I, which illustrates an alternative construction of certain parts of the apparatus;

Fig. IV is a central vertical section—similar to that of Fig. I—through a second illustrative embodiment of this invention;

Fig. V is a partial plan view—on the plane V—V of Fig. IV—of a portion of the construction shown in Fig. IV;

Fig. VI is a reduced scale section on the horizontal plane VI—VI of Fig. IV;

Fig. VII is a second horizontal section on the plane VII—VII of Fig. IV; and

Fig. VIII is a vertical section, in the plane of Fig. IV, showing a slight modification of a part of the construction depicted in that figure.

Referring first to the illustrations of Figs. I, II and III; 1 indicates a forehearth, which extends out from the front of a suitable glass melting tank (not here shown), and which is conveniently enclosed by a sheet metal boot 2, that is supported, at its outer end, by vertical posts or standards 3—3. The forward portion of the forehearth chamber (C) is provided with a removable bell B, which is inserted through the floor of the forehearth, and is held up, in sealed engagement with the roof block 4, by means of a support plate 5 and the bolts 6—6; and the lower end of this bell is partially closed by a flanged metal ring 7, which is held in position by the collar 8 and an insulating bushing 9, of asbestos fibre or equivalent material, and which forms the delivery (flow) orifice of the feeder. The upper end of the bell B is cylindrical in outline, but the lower

part is of rectangular shape, and is provided, on its rear side, with an upwardly tapered and transversely curved portion 10, which is recessed to form a lateral extension 11 of the bell chamber 5 D. The lower end of the recess 11 terminates in a curved port or supply passage G, which passes through the wall of the bell B, and is in registry with a notch in the adjacent side of a second bell member 12 that is inserted through the roof 10 of the forehearth 1 and is held down against the floor of the chamber C by the plate and bolt elements 14—15—15, etc. The member 12 is hollowed out to form an accumulation chamber J, which is in communication with the molten glass 15 in the forehearth extension through the side ports H—H, and the upper end of this member is provided with a tubular bolt 16, of nichrome, or other suitable alloy, which extends up through the plate 14 and terminates in a central cup 17 thereon. The port G is controlled by a reciprocable plug valve 18, which extends through the roof block 4, and which is rigidly secured to the metal collar 19 by the bolt 20. The central stem of the collar 19 is closely engaged by a graphite or asbestos packing gland sleeve 21, which is mounted in the lower head of a cylinder 22, that is bolted to the roof plate of the forehearth boot 2; and the upper end of this stem is secured, by the stud bolt 24, to the piston 25, which is adapted to slide 20 in the upper portion of the said cylinder.

The space below the lower head of the cylinder 22—which is in open communication with the segregation chamber D in the bell B—is connected, by the pipe 28, with the valve chamber of a reciprocable needle valve element 27 that is adapted to regulate the flow of compressed air from the conduit 28 to the chamber D; and the space above the piston 25 is connected, by the pipe 30, with the box of a double acting piston valve 31, which serves to alternately establish communication between the said piston chamber and the pressure and vacuum conduits 32 and 33. This double acting valve assembly, is also coupled, by the pipe 35, to the cup 17, which communicates 40 with the collection chamber J, and further serves to alternately connect the vacuum and pressure lines 33 and 32 to the said chamber J.

The reciprocable valve elements 27 and 31 are positively moved in one direction by the rotating 50 cams 36 and 37 (which are mounted on a common driving shaft but which may be angularly adjusted with respect to each other); and are moved in the reverse direction by the return springs 38 and 39. The stem 40 of the needle valve 27 is 55 pivotally connected to the lower end of a cam lever 41, which is fulcrumed on an adjustable pin 42 that may be moved up and down (in the slotted extremity of the lever 41) to alter the throw of the valve head 27; and the degree of opening 60 of the valve—for any given setting of the pin 42—may also be independently varied by the axial adjustment of the threaded valve sleeve 43 through which the inner end of the valve stem 40 passes. The outer end of this stem carries 65 a disc valve 45, which is normally held closed by a light spring 46, but which is adapted to be engaged, and opened, by an adjustable collar 47 on the stem 40, when the valve head 27 is moved to its closed position by the return spring 38.

70 The functional operation of the above described parts is as follows: When the valve control elements are in the positions shown in full lines in Figs. I and II the upper end of the cylinder 22 is in communication with the compressed air line 32; the connected piston and plunger valve

elements 25 and 18 are depressed until the adjustable stop nut 50, on the upper end of the stud bolt 24 is engaged by the upper head of the cylinder 22; and the supply port G is thereby substantially closed. The compressed fluid then admitted to the upper end of the chamber D (through the pipe and valve connections 28—43—27—26, etc.) supplements the action of gravity in expelling the molten glass from the orifice F, at a rate which is determined and controlled 10 by the line pressure in the conduit 28, and by the adjustment of the valve elements 42, 43 etc., and also, if desired, by the setting of the hand valve 51. During this stage of the operation the line 35 which leads from the accumulation chamber J is connected to the vacuum conduit 33; and the reduction in pressure in this chamber draws the glass from the forehearth pool, through the inlet ports H, H, and rapidly raises the level of the molten material in the interior of the bell 12. 20 In order to definitely limit and preadjust the volume of glass thus admitted to the accumulation chamber, I provide an automatically operated check valve 52 (or 52a Fig. III), which acts to close the lower end of the pipe 35 when the 25 glass has reached a predetermined level, and thus arrests the further action of the vacuum (suction) on the inflowing material. In the construction shown in Fig. I this automatic closure of the check valve (52) is effected by a float 55, of clay 30 or other suitable material, which is adjustably connected to the valve 52 by a threaded stem 56, that passes loosely through the opening in the tubular bolt 16. When the valve is closed by the lifting of the float 55, a hydrostatic balance is at 35 once established between the glass within and without the bell 12; and the elevated column of glass will remain in equilibrium in the now completely closed chamber (J) until the cam 37 acts to lift the piston valve 31.

In the arrangement shown in Fig. I the cams 36 and 37 revolve in a clockwise direction; and these revolving elements are preferably so adjusted that the valve 27 will be momentarily closed—thus cutting off the application of pressure to the glass in the delivery chamber D—before the valve 31 is lifted by the cam 37. The reduction in pressure on the glass above the delivery orifice will diminish the rate of extrusion therefrom, and will produce a natural “necking” 45 of the outflowing stream, without interrupting the continuity of its movement; and the degree of this “necking” action can be regulated and controlled, by the length of the depressed portion of the cam 36, and also by the adjustment of the 50 collars 47 which determine the amount of venting action effected by the relief valve 45. Concurrently with, or immediately subsequent to, the establishment of this temporarily decreased pressure in the chamber D the valve 31 is raised to its 55 upper position, by the cam 37, and the vacuum line 33 is thus put in communication with the top of the cylinder 22 (through the valve port 57 and the pipe 30), while the pressure conduit 32 is concurrently connected to the line 35 through the 60 valve port 58. The exhaustion of the air from the space above the piston 25, permits the latter to be lifted, by the unbalanced pressure of the atmosphere on its lower side, until the end of the piston bolt 24 engages the adjustable stop 65 screw 60, and thereby opens the supply passage G by a predetermined amount. The simultaneous admission of compressed air to the pipe line 35 opens the closed check valve 52, and thus subjects the glass in the chamber J to a predeter- 70 75

mined pressure, (which may be adjusted and controlled by the hand valve 61), that will force it, through the passage G, into the segregation or delivery chamber D, more rapidly than it can escape therefrom through the delivery orifice F, and will therefore quickly raise the level of the glass therein;—this result being effected by making the area of the passage G substantially greater than that of the two inlet ports H—H, and also greater than that of the delivery orifice F, and by also so adjusting the valve controls 27—42—43—51 and 61, that the pressure in the line 26 is substantially less (at this stage in the cycle of operation) than that in the line 35.

In order to further control the automatic action of the feeder I have provided means whereby the valve 31 is returned to its normal full line position of Fig. I (independently of the movement of the cam 37), when the glass has risen to a predetermined level in the delivery chamber D. As shown in Fig. I this means comprises a pair of contact rods 62 and 63, one of which (62) is adjustably mounted (for up and down movement) in an insulated bushing 64 on the base of the cylinder member 22; and the other of which is fixed in an insulated block 65, that is secured to the floor of the forehearth boot 2. These contact rods are connected, by the wires 66 and 67, to the terminals of a magnet coil 68, which is in series with a battery (or other suitable source of electric current) 70; and which is adapted (when energized) to act on a soft iron armature 71, that is carried on a bell crank lever 72, and is normally held away from the coil by the spring 73. The vertical arm of the bell crank lever 72 carries a stop pawl 74, which is adapted to engage the lower end of the valve stem 34, when the valve 31 is lifted by the cam 37, and to hold it in its lifted position after the raised portion of this cam has passed under and beyond the contact roller of the cooperating cam lever 44. But as soon as the rising column of glass in the chamber D comes into contact with the lower end of the rod 62 the battery circuit through the elements 62—66—68—67—65—63 is closed; and the armature 71 is drawn downward and disengages the pawl 74 from the valve stem 34; thus permitting the valve 31 to be returned to its initial full line position by the spring 39. This return movement again admits compressed air to the top of the cylinder 22 (thereby depressing the plug valve 18 and closing the passageway G) and applies vacuum to the chamber J to recharge the latter with a fresh supply of glass.

It will be apparent that the above described assembly of operative parts constitutes a self-controlled system, in which the volume of glass that is drawn into the accumulation chamber J is automatically regulated by the adjustment or setting of the float 55 with respect to the check valve 52; and in which the amount of molten material, that is transferred from this chamber J to the chamber D, is also automatically limited by the vertical adjustment of the contact rod 62; and that the termination of these charging and transfer movements of the glass is in no way dependent upon the mechanical action of the cam 37 and of its associated parts. This automatic self-control of the alternate vacuum and pressure actions on the glass in the chamber J permits the use of a very high vacuum during the accumulation period (which will in turn permit the use of relatively small inlet ports H—H); and also the use of a high pressure during the transfer period—which will result in a very rapid

recharging of the delivery chamber D—without any danger of unduly prolonging either of these operations and without requiring any exact timing, or adjustment of the cam 37. The only function performed by the latter is that of initiating the transfer movement of the glass from the previously filled chamber J to the partially empty chamber D.

It will also be apparent that the total volume of glass discharged from the delivery orifice during any one complete cycle of operative action—i. e., during each complete revolution of the cam assembly 36—37—is controlled in part by the combined gravity and air pressure on the mass of glass above the delivery orifice F, and in part by the degree of throttling exercised by the plunger valve 18 (which may be regulated by the adjustment of the stop elements 58 and 60); and that the relative rate of extrusion of the molten material at successive intervals during each complete cycle may also be varied and predetermined, by the adjustments of the valve elements 27—43—42 and 47, in such manner as to obtain a wide range of "shapes", or diametrical changes of form, in successive sections of the outflowing stream.

The construction shown in Figs. I and II also comprises means for effecting a continuous current movement of the molten glass through the channel between the side walls of the bell members 12—B, and the adjacent walls of the forehearth chamber, and thus preventing the formation of stagnant pools of material, and of localized zones of varying, or variable, temperature. This circulatory movement is produced by a rotating multi-(2)-lobed paddle wheel 77, of suitable refractory material, which is mechanically keyed to the inner end of a large hollow shaft of heat resistant metal (e. g. nichrome) that is revolvably mounted in a graphite bushing 78 and is driven, from any suitable source of power, by the sprocket wheel and sprocket chain element 79—80. The rotation of this lobed wheel maintains a continuous current flow of molten glass in one direction—e. g. a counter-clockwise flow around the front of the bell B—and a reverse circulation of the heated gases of combustion above the glass surface; and this circulatory equalization effect may be assisted or supplemented, if desired, by the use of suitably positioned burners (not here shown) to supply additional heat to the forehearth chamber.

It is also desirable to provide means for blocking off the flow of glass to the forward end of the forehearth chamber for the purpose of removing and (or) replacing one or both of the bell members (12—B), when the latter have been accidentally cracked or injured. As here illustrated this means comprises a vertically movable block 81, whose lower end is immersed in the glass, and whose width is somewhat greater than the gap between the inner ends of the two baffle or bridge blocks 82—82, that project laterally from the side walls of the forehearth chamber. The upper end of the vertically movable gate 81 extends up through the roof of the forehearth, and is preferably covered by a removable cap 83, which is bolted to the top plate of the boot 2, and which serves to prevent any outflow of hot gases through the opening for the member 82. The vertical adjustment of this gate—either for the purpose of restricting the forward movement of the glass through the bridge block gap, or for the purpose of cutting it off completely—can be effected by a threaded hand wheel 85, which en-

gages with a reinforcing bolt 86 that is secured in, and to, the block 81.

Fig. III illustrates another means for arresting the withdrawal of air from the accumulation chamber J when the glass therein has risen to a predetermined level. In this arrangement the automatic closure of the vacuum line connection 35 is effected by a vertically movable disc valve 52a, which is normally held open by a weighted armature 88, that is positioned below an electro-magnet coil 89, and which is closed by the lifting of this armature when the magnet is energized. One terminal of this coil is connected to the battery lead 61, and the other terminal to an insulated cover nut 90 which carries a vertically adjustable threaded rod 91, that passes down through the tubular connecting bolt 56. When the rising column of glass in the chamber J comes in contact with the lower end of this rod (91) the battery circuit is closed, through the contact 63 (see Fig. I) and 91, and the check valve 52a is lifted to its seat, and is held in that position until compressed air is again admitted to the line 35 and forces it open against the pull of the electromagnet.

Figs. IV, V, VI, VII and VIII illustrate another exemplary construction, which presents the same general features of functional action and performance as are characteristic of the previously described assembly (Figs. I to III); but which differs therefrom in certain details of structural form and arrangement of parts. In this structure the forward portion of the forehearth chamber (C) is provided with a raised shelf 94, which rests on the spacing blocks 95-95, and is engaged, on its lower surface, by a cylindrical sleeve 96, that projects up through the forehearth floor and is removably held in sealed contact with the said shelf by the plate and clamp bolt elements 5a-6a. The spacing block and sleeve members 95-95-96 are so shaped and arranged as to form an elongated annular passageway G between the forehearth floor and the shelf 94, (see Fig. VII) and the latter is provided with three openings 98, 99 and 100, which are respectively in registry with the two ends of the passageway G and with the upper end of sleeve 96.

The segregation or delivery bell member B consists of a straight cylindrical sleeve whose lower end is seated on the upper surface of the shelf block 94 and whose upper end is engaged by the chamfered roof block 4a, that is held in position by the cover plate and clamp bolt elements 101-102 etc.;—the inner diameter, and the position, of the member B being such that its lower end embraces both of the openings 99 and 100. The opening 100, which leads from the passage G to the segregation or delivery chamber D, is controlled by a vertically reciprocable plug valve 18a which passes upward through the roof block 4a, and is clamped at its upper end to a guide shaft 19a that is slidably engaged by a graphite bushing 21a in the cover cap 22a.

The opening 98, in the rear part of the shelf 94, is of conical form and is covered by the lower end of a vertically reciprocable bell 12a, which is attached to the lower extremity of a guide rod 104, by the tubular bolt 16a and the auxiliary washer and bolt elements 105-105. This guide rod 104 is provided with a flanged collar 106, which is rigidly secured to the concentric bolt and rod members 16a-104, by the stud bolt and nut elements 107; and this collar is pivotally connected, at 108, to the inner ends of twin arm levers 109-109, which are fulcrumed, at 110, on

a block 111 that is mounted to slide horizontally in suitable guide supports 114. The outer ends of the lever arms 109-109 are flexibly connected to the slotted head of the guide shaft 19a by the cross bolt 115, and carry an adjustable counter-weight 116, which serves to assist in normally holding the plug valve 18a in its closed position; and in concurrently holding the bell member 12a in its raised position. A second pair of rocking guide arms 118-118, are fulcrumed on fixed trunnion supports 119-119 (which lie in the same horizontal plane as the trunnion support 110 of the levers 109-109), and are pivotally connected to the levers 109 by the cross bolt 120, which is positioned midway between, and in line with, the pivot points 108 and 110. The arms 118-118 are also extended inwardly, beyond the trunnion supports 119, and carry a second adjustable counterweight 116a, which cooperates with the weight 116 in holding the members 12a and 18a in the normal full line position of Fig. IV.

The above described system of levers and lever connections—(109-118-108-110-111-114-119 and 120)—constitute a "straight line" linkage which will constrain the rod 104 to move up and down in a vertical line (or at right angles to the plane of the trunnion supports 110-119), and will thus eliminate the necessity for any guide bearing for the lower end of this reciprocable member. The upper end of the rod is secured to a piston 121 which slides up and down in a cylinder 122 and which may be forced down by the admission of compressed air that is admitted to the cylinder space above the piston through a double acting poppet relief valve 123. The downward movement of the connected members 121-104 and 12a is limited by an adjustable nut 60a, which is carried by the upper end of the piston rod 104; and their upward movement—which is accompanied by a corresponding reverse movement of the parts 18a-19a—is controlled by an adjustable set screw 50a that is carried by the head 22a and is adapted to engage the counter-weight 116.

The interior of the head 22a—which is in open communication with the chamber D—is connected, by the pipe 30a with a cam actuated valve assembly (36a-38a-41a-40a-43a-27a-45a etc.) which is, in all essential respects, the same as that illustrated in Fig. I, and which therefore requires no further explanation. But in the arrangement shown in Fig. IV the adjustable movement of the valve cam lever 41a is utilized to not only regulate the flow of compressed fluid to the interior of the bell B—and thereby vary and control the rate of extrusion from the delivery orifice E—but is also used to open the valve 123 and thereby effect the transfer of a fresh charge, or quota, of molten material from the bell chamber J to the delivery chamber D. This action is effected as follows:

When the depressed, or cut away, portion of the revolving cam 36a passes under the roller on the cam lever 41a, the latter is rotated in a clockwise direction (on its adjustable fulcrum pin support 42a) by the pull of the spring 39a; and the valve 27a is moved towards its seat by the return spring 38a, thus momentarily reducing or relieving the air pressure in the delivery bell chamber D. The downward movement of the right hand end of the lever 41a brings an adjustable contact screw 125 into engagement with the adjacent horizontal arm of a bell crank lever 126—which is pivotally connected to the upper

end of the double disc poppet valve 123—thereby closing the atmospheric exhaust port 121, and concurrently opening the subjacent port connection to the conduit 32a. This valve movement 5 admits compressed air to the upper end of the cylinder 122 and moves the connected piston-rod-bell members 121—104—12a downward; thereby shutting off, or throttling, communication between the glass in the chamber J and the surrounding 10 mass of glass in the forehearth chamber C, and simultaneously opening the port connection 99 between the passageway G and the delivery chamber D. The downward movement of the hollow piston rod 104, establishes communication 15 between a lateral port opening 128 in the side of this rod and the space above the piston 121; and thereby admits compressed air to the interior of the depressed bell 12a. The pneumatic pressure thus exerted on the now confined 20 mass of glass, in the accumulation chamber J, forces the molten material, through the connected passages 98—G—99, into the segregation chamber D, at a substantially greater rate than it can be expelled from the delivery orifice F; and this transfer or recharging action will 25 continue until the glass in the bell B has reached a preadjusted height, which is determined and controlled in the following manner:

A vertically adjustable contact rod 62a is passed 30 through an asbestos packed opening in the roof block 4a and is projected downward into the underlying delivery chamber D. The upper end of this rod is threaded and is engaged by a nut 130, which is rotatably mounted between insulating 35 collars carried by laterally projecting lugs on the head 22a; and the rod is connected, by the wire 66a, with one terminal of an electromagnet coil 68a. A second contact rod 63a is extended through the side wall of the forehearth, 40 and the adjacent portion of the spacing block 95, and is projected into the molten glass at the front end of the passageway G (just below the opening 79); and this rod is connected, in series with the battery 70a, with the other terminal of the coil 68a. This coil is provided with a soft iron 45 armature core 71a, which is normally held in its raised position by a compression spring 73a, and which carries an upwardly projecting beveled tooth 74a, that is adapted to engage with the adjacent lower extremity of the bell crank lever 126, and lock the latter—and the attached valve 123—in its "open" position; i. e., in the position to which it is moved by the clockwise rotation 50 of the cam lever 41a. When the glass in the delivery chamber D has been raised to the level indicated by the dotted line in Fig. IV, the battery circuit is closed—through the coil 68a and its connections 62a—63a—66a—71a etc.—and the armature 71a is drawn down, thereby releasing 55 the valve lever 126 from the locking dog 74a, and permitting the valve 123 to be returned to the full line ("closed") position shown in Fig. IV, by the pressure on the air on the under side of its disc heads. The closing of the valve 123 allows 60 the compressed air in the connected piston and accumulation chambers to escape through the atmospheric exhaust port 121; and the members 12a and 18a will then be returned to their original positions (as shown in Fig. IV) by the counterweights 116 and 116a.

When the member 12a is lifted, to the normal full line position of Fig. IV, the chamber J is open to the atmosphere through the restricted vent 132 (which is automatically closed when the piston rod 104 is moved down), and the glass in

the forehearth chamber will then flow freely into the accumulation reservoir—through the large annular opening between the lower end of the raised bell and the shelf 94—until it reaches the level of the molten material in the main pool. 5 But it is of course possible to provide an arrangement whereby the vent 132 will be brought into registry with a port leading to a vacuum line, when the piston rod 104 is raised to cut off communication between the port 128 and the top 10 of the cylinder 122, and thus apply a suction to the glass in the chamber J, which will lift it to any desired height above the level of the glass in the forehearth chamber. Such a modified construction is shown in Fig. VIII, in which 133 is 15 an internally grooved and radially perforated collar that is interposed between two packing rings, or gland members, which embrace the upper end of the piston rod 104; and 35a is a vacuum line connection which leads to an annular 20 channel 135 that surrounds this collar and communicates with the radial perforations therein. When the first described arrangement (of Fig. IV) is used the maximum height of glass in the accumulation chamber is determined only by the 25 level of glass in the main tank and forehearth extension therefrom; and this will remain constant as long as the main tank level is unchanged. With the last described arrangement (of Fig. VIII) the maximum elevation of the glass in the 30 bell 12a will be preferably fixed and determined by mounting a vertically adjustable contact rod 91a in the tubular piston shaft 104, and utilizing this, in conjunction with the contact 63a and a 35 suitable battery (e. g. 70 or 70a), to close an electric circuit through the electromagnet coil 89a, and thereby close the cut off valve 52a, when the glass in the chamber J comes in contact with the lower end of the rod 91a; (see also description of the analogous control illustrated in Fig. III 40 supra).

In order to prevent the escape of hot gases of combustion through the opening around the upper part of the vertically movable bell 12a, I preferably employ a cylindrical guard sleeve 136 45 whose lower end is seated on the shelf block 94, and whose upper end is engaged by a flanged cap 137, that is bolted down to the cover plate 101, and is flexibly coupled to the piston rod collar 106 by the metallic bellows 138. The lower portion of this guard sleeve is cut away on the rear side (as shown in Figs. IV and VI), to afford communication between the glass in the forehearth chamber and the space surrounding the bell 12a; but the sides of the sleeve adjacent to the fore- 50 hearth walls are engaged by bridge blocks 140—140, which rest on the shelf 94 and extend above the level of the glass pool, so that these blocks and the intervening portion of the sleeve 136 together form a dam that cut off the flow of molten 55 material to that part of the forehearth enclosure in which the bell B is mounted. In order to maintain this portion of the feeder assembly at the proper temperature I provide suitable gas burners 141—141 etc., which are preferably 60 mounted at different levels on opposite sides of the forehearth; and are so positioned (see dotted lines of Fig. VI), as to direct oppositely moving currents of hot gases around the front of the bell B, and rearwardly along the sides thereof, 65 through the openings between the upper part of the guard sleeve and the adjacent walls, and into the main tank end of the forehearth chamber. This arrangement eliminates the necessity of 70 providing any special flues or chimneys for car- 75

rying away the burned gases of combustion from the forehearth, and facilitates the establishment and maintenance of uniform temperature conditions in all parts of the forwardly advancing 5 quotas of glass which are successively supplied to the delivery chamber D and then expelled therefrom in a continuously flowing stream.

As already stated one of the features of my present improvements is the provision of a special form of a metal bushing or ring to define and determine the form and the area of the flow orifice F. The clay rings or collars which are ordinarily used for this purpose are subject to mechanical attrition, as well as to the solvent action 10 of the acid silicate constituents of the molten glass; and are also subject to injury in the plugging and unplugging of the flow orifice at the beginning and the end of each week's run; and all 15 of these actions tend to alter both the size and the shape of the opening through which the molten material is extruded, and thereby vary the cross sectional form or (and) the desired rate of delivery of the outflowing stream. In 20 order to avoid these difficulties, and at the same time avoid any substantial cooling of the stream surface by thermal conduction, I provide a flow bushing (7 or 7a), which has a very thin cross section, and is made of highly refractory metal, (e. g., nichrome or tungsten-molybdenum alloy); 25 and insulate this ring from its collar support (8 or 5a) by a thick washer (9 or 9a) of asbestos or other non-conducting material. The internal surface of this metal bushing (7 or 7a) may be accurately machined to a predetermined size and 30 shape (of either circular, or elliptical or other desired cross sectional form), and may also be highly polished; and it will very quickly become uniformly heated to substantially the same temperature as that of the glass in contact therewith; so that it will not only serve to accurately 35 determine the contour of the stream which issues from the delivery orifice (F) but it will also serve to diminish any retardation of the outflow by frictional resistance or by surface chilling.

40 In the normal operation of my improved feeder, suitable means will be provided for severing the extruded and constantly flowing stream of molten material, at proper intervals, to form a succession of mold charges; and for delivering 45 these successively cut off masses to the forming machine. This means may comprise a pair of movable shear blades (S—S)—such as are indicated in dotted lines in Fig. I—which are preferably positioned quite close to the lower end of the 50 delivery orifice F, and are operated at any desired time in the cycle of feed action—(preferably just after the air control valve assembly 27—45, etc., (or 27a—45a, etc.) has temporarily reduced or relieved the fluid extrusion pressure on the 55 glass in the chamber D, and has thereby produced a natural “necking” in the outflowing glass stream)—by a cam actuated device that acts in synchronism with the cams 36 and 37 (or 36a). Various forms of shear mechanism, which are 60 particularly well adapted for use in conjunction with this type of “continuous forced flow” feeder, are fully illustrated and described in my copending applications Ser. Nos. 687,043, filed Aug. 28, 1933, 653,081, filed Jan. 23, 1933, and 701,636, filed Dec. 9, 1933, but as this severing means forms 65 no part of the particular feature of improvement herein set forth (except as complementary thereto) no further description thereof will be given.

I desire it to be understood that I have devised 70 various structures and procedures for producing

and utilizing a continuously flowing stream of molten glass in connection with the formation of mold charges and in which the flow of glass through the orifice is never less than a gravity flow under the existing head and that various 5 details of such apparatus and such procedure herein illustrated and described but not claimed herein are claimed in my following co-pending applications 679,889, filed July 11, 1933, 687,042, filed Aug. 28, 1933, 687,043, filed Aug. 10 10, 1933, 716,626, filed Mar. 21, 1934, and 716,627, filed Mar. 21, 1934.

It will be readily understood, without further extended explanation, that all of the operative portions of my improved feeder assemblies are 15 so constructed and arranged that they may be individually removed from the forehearth boot supports (2 and 3 or 2a and 3a) whenever it is necessary to replace injured or worn out parts; and that the various manual adjustments, which 20 may be used to vary and control the feeding action, are all readily accessible to the operator in charge of the apparatus; and that these adjustments provide for a very wide range of change 25 in the operative conditions, without affecting the inherent self-controlled action of various co-operative elements. And with the preceding disclosure as a guide those skilled in this art will now be able to understand and appreciate the functional characteristics and the operative ad- 30 vantages of the herein described improvements; and will be able to devise various other alternative or equivalent structures which will be capable of practicing my present invention, and of attaining, in whole or in part as may be desired, 35 the various objects and results that have been hereinbefore mentioned or are now apparent.

What I claim is:

1. In combination in a glass feeder, a forehearth enclosing an accumulation chamber, and 40 a delivery chamber, a passage between said chambers, means for controlling the delivery of glass from said forehearth to said accumulation chamber, a device for controlling said passage, and means responsive to the glass level within said 45 delivery chambers for controlling said device.

2. In combination in a feeder for molten material, a forehearth, an accumulation chamber and a delivery chamber associated within said forehearth, a passage between said chambers, 50 means for controlling the delivery of molten material from said forehearth to said accumulation chamber and from said accumulation chamber to said delivery chamber, and means dependent on the material level within said chambers for controlling said first mentioned means. 55

3. In combination in a feeder for molten material, a forehearth, an accumulation chamber and a delivery chamber associated within said forehearth, a passage between said chambers, 60 means for drawing a quota of material from said forehearth into said accumulation chamber, means responsive to material level within said accumulation chamber for controlling said first mentioned means, means for controlling said 65 passage, and means responsive to material level within said delivery chamber for controlling the operation of said passage controlling means.

4. In combination in a feeder for molten glass, a forehearth, an accumulation chamber and a delivery chamber associated with said forehearth, a passage between said chambers for delivering 70 glass from the accumulator to the delivery chamber, a device for controlling said passage, and means for operating said device to close said 75

passage and for drawing glass into said accumulator chamber while discharging glass from said delivery chamber.

5. In combination in a feeder for molten glass, 5 a forehearth, an accumulator chamber and a delivery chamber associated with said forehearth, a passage between said chambers for delivering glass from the accumulator to the delivery chamber, a device for controlling said passage, and 10 means for operating said device to close said passage and for drawing glass into said accumulator chamber while discharging glass from said delivery chamber and means responsive to the glass level within said chambers for controlling 15 the operation of said first mentioned means.

6. In combination in a glass feeder, a forehearth, a delivery chamber having a submerged flow orifice associated with said forehearth and 20 an accumulator chamber communicating with said delivery chamber, automatic means for controlling the delivery of glass from said forehearth to said accumulator chamber and from said accumulator chamber to said delivery chamber and means responsive to glass levels within said chambers for controlling said automatic means.

7. In combination in a glass feeder, a forehearth enclosing a delivery chamber having a submerged flow orifice and an accumulator chamber, a submerged passage between said chambers, 25 means for reciprocating said accumulator chamber to establish and cut off communication between said passage and said forehearth, and a mechanically actuated device for opening and closing said passage.

30 8. In combination with a forehearth for molten glass having a flow orifice associated therewith, a closure for said forehearth, a gate extending through an opening in said closure and projecting into the glass contained within said forehearth, 35 a shield secured to the outer surface of said closure and enveloping the end of said gate projecting through said opening and means extending through said shield for actuating said gate.

9. In combination in a feeder for molten glass, 40 45 a forehearth enclosing a delivery chamber having a submerged flow orifice, an accumulator, a passage between said chamber and said accumulator, means for reciprocating said accumulator, means for closing said passage and means for simultaneously subjecting said chamber to super- 50 atmospheric pressure and said accumulator to sub-atmospheric pressure.

10. In combination in a glass feeder, a forehearth, a delivery chamber located within said 55 forehearth and provided with a submerged flow orifice, an accumulator chamber, an inverted bell mounted within said accumulator chamber, a passage between said chambers, a device for opening and closing said passage, and counterbalanced means for reciprocating said bell and said device.

11. In a feeder for molten glass, a forehearth, a delivery chamber located therein and provided with a submerged flow orifice, an accumulator 60 chamber, a submerged passage between said chambers, an inverted bell located within the accumulator passage, a reciprocatory device located within the delivery chamber for controlling said passage and associated means for lifting said bell as said device is lowered to close said passage and means for simultaneously subjecting the interior of said bell to vacuum pressure and said chamber to super-atmospheric pressure.

75 12. In combination in a glass feeder, a fore-

hearth, a delivery chamber located within the forehearth and having a submerged orifice formed therein, means for segregating a quota of glass from said forehearth while a previously segregated quota is discharged from said delivery chamber and means responsive to glass level within said chamber for controlling the delivery of segregated quotas thereto.

13. A method of delivering a succession of mold charges from a pool of molten glass which consists in withdrawing and segregating a quota of glass from said pool, transferring glass from said segregated quota to a glass delivery position, controlling the amount so transferred by the level of the glass in such delivery position and discharging such transferred portion while withdrawing and segregating a succeeding quota from said pool.

14. A method of delivering mold charges from a pool of molten glass which consists in successively withdrawing and accumulating quotas of molten glass from said pool, transferring a measured portion of each such accumulated quota to a body of glass maintained over an open flow orifice and severing a mold charge from the stream flowing through such orifice while withdrawing and segregating a succeeding quota from said pool.

15. In combination with a forehearth having a discharge orifice, a delivery chamber above 30 said orifice, an accumulator chamber and a passageway joining said chambers, means for subjecting the interior of said accumulator chamber to a vacuum pressure, means responsive to the glass level within said chamber for controlling the operation of said means, means for moving the glass in said accumulator chamber through the passageway and into said delivery chamber, means for closing said passageway, means responsive to the glass level with said delivery chamber for operating said closing means, and means for subjecting the glass within the delivery chamber to super-atmospheric pressure.

16. In combination with a forehearth having a discharge orifice, a delivery chamber, an accumulator chamber and a passage joining said chambers, means for segregating a quota of molten glass within said accumulator chamber, means for moving glass from the accumulator chamber through the passage and into the delivery chamber, means for closing said passage, means responsive to the glass level within said delivery chamber for operating said closing means, and means for subjecting the interior of the delivery chamber to super-atmospheric pressure.

17. In combination with a forehearth for molten glass having a flow orifice therein, an inverted bell projecting into said forehearth and extending below the level of glass contained therein, means for reciprocating said bell, a ported sleeve surrounding said bell and projecting into the glass in said forehearth, a hollow member adjacent said sleeve and in communication with said bell and said orifice and means for alternately connecting said bell and said hollow member to a source of fluid pressure.

18. The method of delivering molten glass from a pool of such material which consists in segregating a quota of material from said pool, transferring a portion of the segregated material to 70 a delivery position, controlling the quantity of material so transferred by the glass level in the delivery position, discharging said transferred material while preventing a reversal of flow from the delivery position and segregating another 75

quota from said pool simultaneously with the discharging of the transferred material.

19. The method of delivering molten glass from a pool of such material which consists in segregating a predetermined quota of material from said pool, transferring a portion of the segregated quota to a delivery position, utilizing the level of material in the delivery position to control the amount of segregated material transferred thereto, discharging the transferred material while preventing a reversal of flow from said delivery position and segregating another quota simultaneously with the discharge of the transferred material.

15 20. A pneumatic glass feeder comprising a forehearth having a flow orifice therein, a delivery chamber in communication with said flow orifice, an accumulation chamber communicating with the forehearth and having a passage leading 20 therefrom into said delivery chamber, a closure member for said passage, means for alternately connecting said accumulation chamber to sources of fluid pressure and vacuum, means for periodically connecting the delivery chamber to a source 25 of fluid pressure and means for moving said closure member into passage-closing position each time said delivery chamber is connected to the source of pressure.

21. A pneumatic glass feeder comprising a forehearth having a flow orifice therein, a delivery chamber in communication with said flow orifice, an accumulation chamber communicating with the forehearth and having a passage leading 30 therefrom into said delivery chamber, a closure member for said passage, means for periodically connecting said accumulation chamber to a source of fluid pressure to move material therein through the passage into said delivery chamber, means for periodically connecting said delivery chamber to a 35 source of fluid pressure, and means operable when said delivery chamber is connected to pressure for moving said closure member into passage-closing position.

22. A pneumatic glass feeder comprising a forehearth having a flow orifice therein, a delivery chamber in communication with said flow orifice, an accumulation chamber communicating with the forehearth and having a passage leading 45 therefrom into said delivery chamber, a closure member for said passage, means for alternately connecting said accumulation chamber and said delivery chamber to a source of fluid pressure, and means operable when said delivery chamber is connected to the source of pressure for moving 50 said closure member into passage-closing position.

23. The combination with a feeder for molten glass comprising a forehearth having a flow orifice therein, a delivery chamber in communication with said flow orifice, an accumulation chamber communicating with the forehearth and having a passage leading therefrom into said delivery chamber, a closure member for said passage, means for alternately connecting the accumulation 60 chamber to sources of vacuum and fluid pressure to alternately accumulate a quantity of glass therein and discharge glass therefrom into said delivery chamber, means for periodically moving said closure member into said passage-closing position, means responsive to the glass level within 65 said delivery chamber for independently operating said passage-closure member, and means for periodically connecting the delivery chamber to a source of fluid pressure.

75 24. The combination in a feeder for molten

glass comprising a forehearth having a flow orifice therein, a delivery chamber in communication with said flow orifice, an accumulation chamber communicating with the forehearth and having a passage leading therefrom into said delivery chamber, a closure member for said passage, means for periodically connecting the accumulation chamber to a source of pressure to move material therefrom through said passage into said delivery chamber, means responsive to the glass level within said delivery chamber for closing the connection between said accumulation chamber and the source of fluid pressure, means for periodically moving said closure member into passage-closing position, and means for periodically connecting said delivery chamber to a source of fluid pressure.

25. The combination in a feeder for molten glass comprising a forehearth having a flow orifice therein, a delivery chamber in communication with said flow orifice, an accumulation chamber communicating with the forehearth and having a passage leading therefrom into said delivery chamber, a closure member for said passage, means for alternately connecting said accumulation chamber and said delivery chamber to a source of fluid pressure, means responsive to the glass level within said delivery chamber for automatically closing communication between the accumulation chamber and the source of fluid pressure, and means operable when said delivery chamber is connected to the source of fluid pressure for moving said closure member into passage-closing position.

26. The combination in a feeder for molten glass comprising a forehearth having a flow orifice therein, a bell projecting into said forehearth and extending below the level of the molten glass contained therein, a hollow member adjacent said bell and in communication with said orifice, a floor block having an opening therein for establishing communication between said bell and said hollow member, a closure member for said opening, means for reciprocating said bell and closure member, and means for alternately connecting said bell and said hollow member to a source of fluid pressure.

27. The combination in a feeder for molten glass comprising a forehearth having an orifice therein, a bell projecting into the forehearth and extending below the level of the molten glass contained therein, a hollow member adjacent said bell and in communication with said orifice, a floor block having an opening therein establishing communication between said bell and said hollow member, a closure member for said opening, means for reciprocating said bell and closure member, means for alternately connecting said bell and said hollow member to a source of fluid pressure, and means responsive to the level of glass in said hollow member for independently closing the connection between said bell and the source of fluid pressure.

28. The combination in a feeder for molten glass comprising a forehearth, a hollow member supported in said forehearth and having a flow orifice therein, a spout projecting from said member, a stationary bell adjacent said member and having a series of ports therein one of which is in registration with said spout, means for alternately connecting said bell to sources of fluid pressure and vacuum, means responsive to the level of glass within said bell for closing the connection to the source of vacuum, a closure member for said spout, means for reciprocating said

closure member and means operable when said spout is closed for connecting said hollow member to a source of fluid pressure to expel the glass therefrom through the orifice.

5 29. The combination in a feeder for molten glass comprising a forehearth, a hollow member supported in said forehearth and having a flow orifice therein, a spout projecting from said member, a stationary bell adjacent said member and having a series of ports therein one of which is in registration with said spout, means for alternately connecting said bell to sources of fluid pressure and vacuum, means responsive to the level of glass within said bell for closing 10 the connection to the source of vacuum, a closure member for said spout, means reciprocating said closure member, means responsive to the level of glass within said hollow member for actuating the closure member reciprocating means, and 15 means for periodically connecting the hollow member to a source of fluid pressure to expel the glass therein through the orifice.

30. The combination in a feeder for molten glass comprising a forehearth having a flow 25 orifice therein, a delivery chamber in communication with said orifice, an accumulation chamber communicating with the forehearth and having a passage leading therefrom into said delivery chamber, a gate normally closing said passage, 30 means for periodically moving said gate to open said passage, means for applying an expelling force to the glass in said accumulation chamber to transfer glass therefrom through said passage and into said delivery chamber, and means responsive to the glass level within said delivery 35 chamber adapted to control the closing of said gate.

31. The combination in a feeder for molten glass comprising a forehearth having a flow 40 orifice therein, a delivery chamber in communication with said orifice, an accumulation chamber communicating with the forehearth and having a passage leading therefrom into said delivery chamber, a reciprocable closure member for said 45 passage, means for reciprocating said closure member, a valve for controlling the operation of said closure member reciprocating means and adapted to connect said accumulation chamber to sources of fluid pressure, mechanical means 50 for periodically operating said valve and means responsive to the glass level in said delivery chamber for operating said valve independently of said mechanical means.

32. The combination in a feeder for molten 55 glass comprising a forehearth having a flow orifice therein, a delivery chamber in communication with said orifice, an accumulation chamber communicating with the forehearth and having a passage leading therefrom into said delivery chamber, a gate for closing said passage, fluid actuated means for controlling the move-

ment of said gate, means for introducing fluid pressures into said accumulation chamber, a valve for controlling delivery of fluid pressures to said fluid actuated means and to said accumulation chamber, mechanical means for operating said valve and means responsive to the glass level with said delivery chamber for operating said valve independently of said mechanical means.

5 33. The combination in a feeder for molten 10 glass comprising a forehearth, a delivery chamber in open communication with a flow orifice, an accumulation chamber communicating with the forehearth and having a passage leading therefrom into said delivery chamber, a closure 15 member for said passage, fluid actuated means for reciprocating said closure member, a valve for connecting alternately said fluid actuated means and said accumulation chamber to sources 20 of fluid pressure and vacuum, mechanical means for actuating said valve, means responsive to the level of glass within said accumulation chamber for independently closing its connection to the source of vacuum, means responsive to the level of glass within said delivery chamber for operating 25 said valve independently of said mechanical means, and means for periodically applying an expelling force to the molten glass within said delivery chamber.

30. A method of forming a succession of mold 30 charges from a mass of molten glass, which consists in successively withdrawing and accumulating quotas of molten glass from said mass, transferring glass from each such quota to a body 35 of molten glass maintained over a flow office, while proportioning the quantity of glass so transferred in accordance with variations in the head of glass of such body over said orifice, and severing mold charges from the stream issuing from said orifice in timed relation with the accumulation of such 40 quotas.

35. A method of forming a succession of mold 45 charges from a mass of molten glass, which consists in withdrawing a quota of glass from such mass, shutting off communication between the quota so withdrawn and said mass and substantially simultaneously establishing communication between such quota and a body of glass maintained above a flow orifice, delivering glass from such quota to such body to increase the head 50 thereof over said orifice, shutting off communication between said body and the undelivered portion of said quota, and substantially simultaneously establishing communication between such portion of such quota and such mass, continuing 55 the discharge of glass from said body through said orifice while replenishing such quota and repeating the cycle while severing the stream issuing from said orifice in timed relation with such replenishing operations.

60 FRANK L. O. WADSWORTH.
